BUILDING APPARATUS

Stephen Stepanian, Columbus, Ohio

Application August 15, 1941, Serial No. 406,982

3 Claims. (Cl. 25—1)

1

The present invention relates to building structures, and more particularly to apparatus for building structures formed of concrete.

One of the objects of the present invention is to provide a building structure in which a support, intermediate the side walls supports the central portion of the roof and in which the outer portions of the roof floatingly rest on the side walls.

Another object of the present invention is to provide apparatus for forming a building of the character described having a base structure, side walls and roof, and with track means surrounding the same, and which has a pivotally mounted runway supported on the track means, as well as a crane supported thereby to facilitate the distribution of building forming material.

It is also an object to provide building apparatus of the type having a vibratory trowel means, and which has a crane and a pivotally mounted runway therefor supported on track surrounding the building foundation to provide for pivotal movement thereof in a horizontal plane.

Another object of the present invention is to utilize the intermediate support, for the roof, or the base for said support as a pivotal supporting mechanism for a rotating platform or a rotating vibrator.

Other and further objects and advantages will be apparent from the following description, reference being had to the accompanying drawings wherein preferred forms of embodiments of the present invention are clearly shown.

In the drawings:

Fig. 1 is a side view and Fig. 2 is a top view of the completed house;

Fig. 3 is a sectional view of the foundation for the house, the section being taken on line 3—3 of Fig. 4;

Fig. 4 is a top plan view of the concrete foundation;

Fig. 5 is a fragmentary sectional view of the floor and the foundation therefor and showing the apparatus used for forming the floor;

Fig. 6 is a top plan view of the floor and the apparatus shown in Fig. 5;

Fig. 7 is a fragmentary sectional view showing the apparatus for forming the side walls; and

Fig. 8 shows apparatus for pouring concrete in its roof pouring position.

Referring to the drawings, my improved house is shown at 40 which includes basically a concrete base 41, side walls 42, preferably in the form of a cylinder and a roof 43. The roof is provided with a balustrade 45 including posts 46

2

and a rail 47. The chimney is shown at 49. The house is provided with at least one door 50 and windows 51.

The foundation 41, in a cylindrical type house, will include a cylindrical rim 53, a central hub 54 and radially extending webs 55 connecting the hub 54 with the rim 53.

A preferred manner of forming the foundation for the house is to provide first a heavy layer 10 of foundation gravel 58 and this gravel layer is deeper below the hub 54 and rim 53 and webs 55. Cold air ducts 59 are imbedded in the gravel and the hot air ducts 60 have only the upper surface thereof extending above the gravel. It is necessary usually to excavate the ground 61 as shown in Fig. 3, the excavation being made deeper below the hub 54, rim 53 and the ducts 59.

Forms are provided for forming the hub 54, web 55 and rim 53 and then the concrete base 41 is poured. This base is formed of a mixture of aggregate and suitable cement. Bolts 62 are embedded in the hub 54 and the ends thereof extend upwardly. Reinforcing rods 63 are embedded in the rim 53 and have portions 64 projecting upwardly. After the concrete base 41 is formed and the forms removed, the gravel 58 is again retamped. Then a sealing material 65 is spread over the top of the gravel between the webs 55.

Referring now to Figs. 5 and 6, the flange 66 of a socket 67 is secured by nuts 68 to the four bolts 62 in the hub 54. This socket 67 is internally threaded to receive an extending bearing or trunnion 70. A platform or runway 71 is pivotally mounted upon the bearing 70 and the outer end thereof carries wheels 72 which ride upon a track 73. The track 73 is supported on a platform 74 and this platform encircles rim 53 and forms an edge form for the floor 75. The rotating platform 71 carries a rotating crane 76 for a bucket 77. A concrete mixture of suitable aggregate and cement is placed in the bucket 77 and then the crane 76 is swung so that the bucket overhangs the platform 71. The concrete is then dumped into a wheel barrow 78 and conveyed to the center of the foundation. Preferably a sector from the center to the rim is poured onto the foundation and, after such sector is poured, a vibrating movement is imparted to

the concrete for causing the concrete to settle evenly and provide a smooth top surface. Any suitable mechanical type of vibrator may be used and can be operated by a workman standing on the platform 71. In the present embodiment the vibrator support includes an arm 79 having the

inner end thereof pivotally supported on the bearing 70 and the outer end thereof carries one end of a long narrow trowel 82 and this trowel extends from the socket 67 to the platform 74. The end of the trowel adjacent the platform 74 is carried by arm 99 similar to arm 79 and the free end of this arm is supported by a truck 100 having wheels 80 which ride upon the track 73. The trowel 82 carries an electrically operated vibrator 81 for imparting vibratory motion thereto. While one workman is pouring the sector from the platform 71, another workman can be using the vibrator and otherwise level and smooth the top surface of the floor. A ring 83, preferably of wood, is embedded in the top surface of the floor directly above the center of the rim 53. This ring 83 is later removed and provides a depression forming a wall seat 84. The reenforcing rods 63 extend upwardly through the ring 83.

After the floor is laid and hardened, and after the platform 71 is removed, the bearing 70 is removed and a post 85 is threaded into the socket 67. After the ring 83 is removed, resilient sealing material having flow characteristics is inserted into the recessed seat 84. This material is shown at 86. The inner forms 87 for the side walls 42 are then placed in position. These forms are preferably formed of a plurality of sections which extend throughout the height of the wall 42 and the abutting vertically extending edges thereof are bolted to one another, as shown in Fig. 7.

After the reenforcing rods are in position, the outer form 96 is placed in position. This outer form, like the inner form, is formed in a plurality of sections extending throughout the height of the wall and have the abutting ends thereof bolted tightly together. The sections of the outer form 96 are also formed preferably of sheet metal. The upper parts of the form 96 extend outwardly to provide a ledge 97, which in turn forms a gutter 98. The concrete is poured into the space between the forms 87 and 96, preferably by being dumped directly into the upper part of the space and into the gutter 98 whence it flows downwardly into the space. The concrete is elevated by crane 76 which is now carried on an extension 101. This extension is carried by wheels 72 which ride on the track 73. The bearing 70 is threaded into the upper part of the hollow post 85 and the platform 71 is again pivotally mounted on the bearing 70. The outer end thereof is secured to the extension 101 of the crane 76. Thus the platform 71 steadies the crane. It will be noted that the forms 87 and 96 are disposed so that the side walls 42 are concentric with and extend into the seat 84 of the floor 75. The sealing material 86 between the underside of the side walls 42 permits relative sidewise slidable movement of the wall and floor which may be necessary because of relative expansion and contraction of the floor and side walls due to changes in temperature. Several spaced vibrators 81 are removably clamped to the joints of sections 96 and are suspended from gussets 104 by cables 105 and these vibrators are actuated for the purpose of causing settling of the concrete and providing a smooth outer surface. These vibrators can be raised and lowered by cables 105 and are clamped at different heights during the pouring operation.

A collar 106 is secured to the center post 85 adjacent the top thereof and this collar carries a disc of concrete 107. This disc is provided with

10 a hole 108 for receiving the upper end of the post 85. Preformed frame structures each comprising posts 110, cross rails 111 and 112, are then placed at desirable places within the enclosure and a floor 113 or the like is laid upon the cross rails 111 and 112 and extends from the periphery of the disc 107 to the inner form 87. A layer of resilient sealing material 116, having flow characteristics, is laid upon the disc 107 and a like sealing material 117 covers the top of the wall 42. The sealing material 116, 117 and floor 113 form a smooth surface which extends to the gutter 98 of form 96 and the concrete roof 43 is then poured onto this surface. This roof 43 is laid in the same manner that the floor 80 is laid, that is, by pouring the concrete from the bucket 77 and into the wheelbarrow 78 whence it is distributed. After it is distributed, it is vibrated by a vibrator 81, carried on the trowel 82. The arm 99 is now carried by an extension (not shown) which rides on wheels 80. The inner end of arm 79 is again pivoted on bearing 70. It is desirable to hold the disc 107 stationary during the pouring operation of the roof and in order to accomplish this the post 85 is braced by braces 120 which are suitably secured to the posts 110.

30 After the concrete roof has set, the frame including members 110, 111, and 112 and the braces 120 are removed and then the forms 87 and 96 are disassembled and removed from the structure. If desirable, the floor 113 can be removed.

The post 85 extends through the roof 43 and forms a center about which the chimney 49 can be built. A hole is cut in the hollow post 85 and a nipple 121 is attached. A furnace pipe or the like can be attached to the nipple, and, the post 85 then functions as a flue.

35 In the preferred embodiment, the window frame and door frame (not shown) are inserted in position before the concrete is poured. These frames are formed of pressed steel which are surrounded by an angle iron. The frames may be hung from the top of the inner form 87 by suitable wires which are fastened to the reenforcing rods 88 and 89 and to the angle iron. It will of course be understood that these frames are hung in position before the reenforcing rods 88 and 89 and the outer forms 96 are placed in position. The vibrating mechanisms 81 cause the concrete to flow and fill the space directly underneath the window frames.

The platform 74 and the track 73 are formed in sections and are removed after the roof is poured.

40 From the foregoing it will be seen that the roof is supported entirely by the center post 85 and the side walls 42. The roof 43 floats on the side walls 42. In this manner the roof 43 can move relative to the side walls 42 and this is desirable because of the relative difference in expansion and contraction of the roof and the side walls. The sealing material 116 and 117 prevents the leaking of air at the joint between the side walls and the roof. If desirable, co-operating hardened bearings may be embedded in the top of the side wall and in the underside of the roof directly above the side walls.

45 By reason of the method of construction, various different designs of footing and heading of the side walls can be obtained. In some cases, it may be desirable to provide a trough for directing the concrete between the forms 87 and 96, while in other types of construction the forms in themselves provide a trough of sufficient width

for receiving the concrete poured thereinto from the bucket 77.

It is apparent that many advantages are present herein. The present invention materially reduces the cost of building houses or the like. The floor and roof can be laid quickly by the apparatus including the rotatable platform and rotatable vibrator carrying arm. The central socket 67, in addition to providing a support for the central supporting post 85, provides a support for trunnion 70 of the platform 71 and vibrator supporting arm 79. Likewise the supporting post 85 provides a support for the trunnion 70 of the platform 71 and arm 79.

Under certain conditions, it may be desirable to construct the building from preformed sections. It is to be understood that the floor can be made in sections and then laid, only the side walls and roof are built from preformed sections.

The roof is built from a plurality of overlapping sections. These sections rest upon the concrete disk 107 (see Fig. 8). The outer ends of the sections overlie the side walls and are free to float.

By providing for sliding movement between the roof 43 and the side walls 42, the cost of construction has been materially reduced since only one additional support is necessary. Since sliding movement is permitted, differences in contraction and expansion between the side walls and the roof and the floor will have no detrimental effect.

Although I have shown the houses as circular in shape, it is readily apparent, to those skilled in the art that the fundamentals of construction and the mechanism employed to form the houses are equally applicable to houses having other than circular shape.

While the forms of embodiments of the present invention as herein disclosed constitute preferred forms, it is to be understood that other forms might be adopted, all coming within the scope of the claims which follow.

I claim:

1. Apparatus for forming a building of the type having a base structure comprising track means surrounding the base structure, a runway, a crane carried by the runway, means pivotally supporting said runway on said base structure, and additional means movably supporting said runway on said track means.

2. Apparatus for forming a building of the type having a base structure and side wall forms extending upwardly therefrom comprising track means surrounding the base structure, vertically extending post means supported by said base structure, and a horizontally extending runway movably mounted on said track means and piv-

otally connected to said post means, said runway being disposed in a plane above the top of the side wall forms and having a crane mounted thereon to facilitate the distribution of building forming material.

3. In building apparatus of the type having vibratory trowel means, the combination of track supporting means for surrounding a building foundation, pivot means formed for attachment to the building foundation, a crane and a runway for facilitating the distribution of floor forming materials over the foundation supporting said crane, said runway and the vibratory trowel being supported on said pivot means and said track for pivotal movement in a horizontal direction.

STEPHEN STEPANIAN.
